DESIGN FOR A SMOKING STAND

Wolfgang Hoffmann, Batavia, Ill., assignor to
The Howell Company, St. Charles, Ill., a corporation of Illinois

Application December 24, 1935, Serial No. 60,262

Term of patent 3½ years

To all whom it may concern:

Be it known that I, Wolfgang Hoffmann, a citizen of the Republic of Austria, residing at Batavia, in the county of Kane and State of Illinois, have invented a new, original, and ornamental Design for a Smoking Stand, of which the following is a specification, reference being had to the accompanying drawing, forming a part thereof.

Figure 1 is a side elevation;
Fig. 2 is a view in plan; and
Fig. 3 is a view in section through the receptacle cap, on line 3—3 of Fig. 2, of a smoking stand exhibiting my new design.

I claim:

The ornamental design for a smoking stand, as shown.

WOLFGANG HOFFMANN.
